UNITED STATES PATENT OFFICE.

HUGH PARK PARIS, OF SEATTLE, WASHINGTON, ASSIGNOR, BY DIRECT AND MESNE ASSIGNMENTS, TO PARIS TRANSIT MIXER CO., A CORPORATION OF WASHINGTON.

APPARATUS FOR HANDLING, MIXING, AND POURING CONCRETE.

Application filed November 5, 1925. Serial No. 67,128.

My invention relates to the handling of concrete and especially to a method and plant whereby concrete can be delivered in large quantities to the job, ready for pouring, without the necessity of employing a concrete mixer on the job, and in such condition that the concrete is made ready by the time it reaches the spot where it is to be poured.

Applied to road building, my invention has for its object the provision of a method, a plant, and apparatus for putting the method into operation, whereby the constituent materials—sand, gravel, cement and water—can be assembled at a convenient central spot located conveniently to the roadway, but not dumped at intervals along the right-of-way, and whereby these materials are conveyed to the end of the roadway, being picked up as the raw materials and being delivered to the job as ready-mixed concrete in a completely homogeneous and thoroughly mixed condition, ready for pouring, thus eliminating the employment of large gangs to load a concrete mixer at the job, and enabling very rapid laying of the roadway by a small number of men.

Thus it will be seen that my invention, in a more general aspect, relates to the handling, mixing and pouring of concrete, whereby the various raw materials are loaded upon a single vehicle (a truck and trailer being of course the equivalent), and conveyed therein to a point of use, the materials being mixed in transit, and being delivered at the point of use, ready to pour at once in the molds.

My invention comprises the novel process and plant as illustrated in diagrammatic form in the drawings, and the novel apparatus also shown in the drawings, both as hereinafter described and claimed.

In the accompanying drawings, I have shown my apparatus in a form which is now preferred by me, it being understood that various modifications may be made without departing from the spirit thereof.

Figure 1 is a diagram of a typical plant employed in the construction of a roadway, illustrating the process of laying the same according to my improved method;

Figure 2 is a side elevation of a combined

truck and mixer employed in carrying out my process; and

Figure 3 is a section on the line 3—3 of Figure 2.

One of the most serious problems in concrete construction is the elimination of the large number of laborers required in the handling of the materials in feeding the concrete mixers. A small number of men only is required in spreading and finishing concrete in roadways or in tamping it in building constructions, but for supplying the concrete mixer with the materials going into the concrete, according to the methods now in use, large numbers of wheelbarrow men and shovels must be employed. It has been proposed to eliminate these laborers by supplying concrete ready mixed from a central plant, carrying it in this condition to the job. It has been found unsatisfactory, however, for the reason that the concrete, containing materials of various gravities, will separate into strata, the separation being caused merely by the gentle agitation as a truck or hopper load of the material is being transported over quite short distances. The result is that the concrete thus delivered is not homogeneous and is not thoroughly mixed throughout. The resulting concrete is of poor quality, with large interstices not filled with sand between the gravel, and with too much sand in other spots.

According to my process I propose to supply what are, in effect, traveling concrete mixers with the materials going into the concrete, such as sand, gravel, cement and water, to transport these materials to the job in such trucks, to cause the mixers, as the trucks approach the job, to mix the materials thoroughly, arriving at the job with the mixing completed but continuing, and dumping the material immediately from the mixer in a condition ready for pouring or spreading. Thus, by the employment of central bunkers the materials may be handled largely without hand labor and can be transported economically over considerable distances. The distribution of the several materials must be accomplished under the methods now in use, in road building, hence it is economy to distribute them in the mixed

condition, handling them once only, at the bunkers, where the greatest economy in handling can be effected.

Referring to Figure 1, the bunkers B may be served by a spur line S of the main line railroad R. The right-of-way A of the road to be laid may pass near the bunkers B and may be connected thereto by a temporary roadway C. Trucks T, in the nature of traveling concrete mixers, and the construction of which will be described more fully hereafter, ply between the bunkers B (a water tank D being located nearby) and the end E of the finished roadway. Several such trucks may be employed, more being employed as the distance from the bunkers to the end of the roadway increases. At the end of the roadway E only sufficient workmen W need to be employed as are required to handle, spread and finish the material as it is dumped on the ground. Such men are required in any instance with the methods now in use, but it will be observed that the materials may be delivered to the bunkers B by dump cars from the railroad and may be delivered to the trucks T without handling by workmen. Thus, practically all unskilled manual laborers may be dispensed with.

Bunkers may be set up at distances, perhaps of every ten miles along the right of way, and trucks will transport the material five miles in either direction from the bunkers to the end of the roadway. These can be arranged to carry up to three yards of material without difficulty, and to mix these materials while traveling or as they approach the end of the roadway. This mixing need only continue two or three minutes. Hence the driver can arrange to start the mixing when within a distance that he can cover in two or three minutes from the end of the roadway. The result will be that he delivers his material thoroughly and freshly mixed and ready for pouring at the end of the roadway, dumps it rapidly and returns to the bunkers for another load. The same method can be employed for structural work, the load of mixed concrete being delivered to an elevator or like conveyor to be delivered immediately to the forms.

As illustrating the apparatus which might be employed in carrying out such a process, as applied to road construction, I have shown the truck illustrated in Figures 2 and 3. The chassis, running gear, power plant and the like may all be of standard design. Mounted upon the chassis 1 is a supplemental dumping frame 2, the two frames being connected for dumping, as by a pivot at 21 at the rear end of the chassis. Upon the frame 2 is mounted a mixing cylinder 3. This is suitably supported to rotate, and may be provided with the flanged rings 30 engaged by pairs of rollers 4, the rollers be-

ing secured upon longitudinal shafts 40, one at each side of the frame 2, and supported in suitable bearings 41. Rotation of the shafts 40 is secured by means of complementary clutch elements 42 and 43, secured respectively upon the end of the shaft 40 and upon the end of a stub shaft 44, supported from the chassis 1 or upon a platform 10, secured thereto. Rotation of the shafts 44 from the vehicle engine or running gear may be obtained by means of sprockets 45 upon the stub shafts 44, connected by chains 46 to sprockets 14 upon the drive shaft 11 of the truck. Many trucks are now provided with a power take-off from the transmission, or are arranged in such a way that power may be taken from the drive shaft itself. Power can, therefore, be supplied to the shafts 44 in any way found convenient, and adaptable to the particular truck employed.

Control of the clutch element 43 may be secured through a suitable lever 47 arranged within reach of the driver's seat. This is engaged while the truck is en route to the job, and must be disengaged from the element 42 prior to dumping of the materials from the mixer 3. For dumping any suitable arrangement may be provided, such as the power hoist now commonly employed, or any suitable hand hoist. As this forms no part of my present invention, I have shown a winch 5 having a cable 51 wound thereon and passing over a pulley 52 at the top of a standard 53, the end of the cable being suitably attached to the swinging end of the dumping frame 2.

Inasmuch as the mixer cylinder 3 merely rests upon the cradle formed by the rollers 4, means must be provided to retain it in position, and as indicative of such means I have provided a band 6 secured to the dumping frame 2 and encircling the upper part of the cylinder, and having rollers 60 mounted therein in position to engage the cylinder 3 if the latter is displaced from its normal position. Normally, however, the rollers 60 will not contact with the mixer. Any suitable arrangement of such retaining frame or bands may be employed and any suitable construction thereof which will serve the purpose may be used.

Water must be carried on the truck, and for this purpose I have shown a tank 15 mounted upon the driver's cab 13, and connecting through a valve 16 in convenient reach of the driver, and by a flexible hose 17, to the interior of the mixer 3.

Materials are delivered into the open end of the cylinder 3 and are carried therein as the truck moves toward the job. Water is supplied from the storage tank D to the tank 15 on the truck at the same time. When within a short distance of the job the clutch elements 42 and 43 may be engaged by the driver as the truck continues to move, and

this commences rotation of the mixer 3. Vanes 33 or like mixing elements may be employed within the mixer, these serving to more thoroughly intermix the materials therein. Water is then supplied by opening the valve 16, and when the truck arrives at the job, the concrete is fresh and ready to pour, wet, and thoroughly mixed. It may continue to mix if the truck for any reason must stand still, as the power take-off would be so arranged that it is connected with a part of the transmission which continues to rotate under such circumstances. When ready to dump, the winch 5 is brought into operation, the forward end of the frame 2 with its cylinder 3 is up-turned, and the mixed concrete is released from the rear end of the cylinder.

The speed of rotation of the cylinder 3 may be arranged to suit the speed of the truck. Ordinarily such trucks will travel at perhaps 15 miles an hour loaded, and the gearing can be arranged to turn the cylinder 3 at a speed of perhaps 15 revolutions a minute. If the speed reduction in the transmission, plus the speed reduction in the sprockets 14 and 45 and plus the reduction obtainable by the use of small rollers 4 to drive the drum, is not sufficient, it will be obvious that speed reduction gearing can be interposed in the drive to the rollers 4, preferably on the platform 10. This, however, is a matter of mere mechanical detail, and it will be understood that the speed of rotation of the drum 3 will be sufficient to secure the most efficient mixing at the normal speed of the vehicle. If the power take-off be more directly connected to the engine than through the drive shaft connecting the transmission to the differential gearing, it will be largely independent of the speed of the truck.

The bunkers B have been shown as of the conventional gravity type, but it should be observed that these are merely typical of a storage and loading station, and that the term as used herein is to be understood as having that meaning. The invention is not dependent on the employment of any particular type of bunker, and would effect an economy even were the materials loaded by hand from large centrally located piles. This would eliminate haulage from central bunkers to the job in gravel trucks, and dumping in separated piles, to be again picked up for loading into the mixer at the end of the roadway.

What I claim as my invention is:

1. A transit concrete mixer comprising an automobile vehicle, a supplemental frame tiltably supported upon the vehicle frame, a mixing element mounted upon said supplemental frame, means on said supplemental frame for securing said mixing element thereon, drive means operatively connecting

said mixing element with the vehicle drive mechanism, and including clutch elements disconnectible to permit substantial elevation of the supplemental frame and mixing element, for dumping. 70

2. A transit concrete mixer comprising an automotive road vehicle, a supplemental frame tiltably supported upon the vehicle frame, a mixing cylinder cradled in said supplemental frame, a hoist for tilting said dumping frame and the mixing cylinder, and means for rotating said cylinder from the vehicle's power plant, including two shaft sections, one on the vehicle frame and one on the supplemental frame, and complementary clutch elements upon the respective sections, and separable prior to dumping to permit hoisting of the supplemental frame and mixing cylinder for dumping. 75 80

3. A transit concrete mixer comprising an automotive road vehicle, a supplemental frame tiltably supported upon the vehicle frame, a mixing cylinder cradled in said supplemental frame, a hoist for tilting said dumping frame and the mixing cylinder, 85 means for rotating said cylinder from the vehicle's power plant, including two shaft sections, one on the vehicle frame and one on the supplemental frame, complementary clutch elements upon the respective sections, 90 and disengageable to permit hoisting of the supplemental frame and mixing cylinder for dumping, and means carried by said supplemental frame for securing said mixing cylinder in position thereon while horizontal 95 or while in dumping position. 100

4. A transit concrete mixer comprising a vehicle, a supplemental frame pivotally connected with the vehicle frame near its rear end, a rotative mixing cylinder, means for supporting said mixing cylinder from said supplemental frame, and means for driving said mixing cylinder from a portion of the vehicle which rotates as the vehicle is moving, said driving means including members 105 separable prior to dumping to permit elevation of the supplemental frame. 110

5. A transit concrete mixer comprising a vehicle, a supplemental frame connected at its rear end to the rear end of the vehicle 115 frame, whereby the supplemental frame may be moved into dumping position, a rotative mixing cylinder, means for supporting said mixing cylinder from the supplemental frame and for securing it thereupon when 120 in transit, and drive means for said cylinder operatively connected to a portion of the vehicle which rotates as the vehicle is moving, whereby the mixing cylinder may be rotated while in transit. 125

6. A transit concrete mixer comprising an auto truck, a supplemental frame supported on the truck chassis, means for moving said supplemental frame relative to the truck chassis into dumping position, a rotative 130

mixing cylinder, means for supporting said cylinder from said supplemental frame, and drive means operatively connecting said mixing cylinder with the truck propelling 5 means to permit rotation of said mixing cylinder while in transit.

7. A transit concrete mixer as in claim 6, said drive means including complementary members, one supported on the truck chassis 10 and the other on the swinging end of the supplemental frame, engageable to rotate the cylinder and prior to dumping to permit the supplemental frame to be raised for dumping.

13. 8. A transit concrete mixer as in claim 6, the drive means comprising a shaft mounted on the supplemental frame at each side of the mixing cylinder, rollers on said shafts and tracks on the cylinder engaged thereby, 20 stub shafts supported from the truck chassis forward of the supplemental frame and each aligned with its respective shaft on the supplemental frame when the latter is in its normal running position, driving means connecting said stub shafts with the vehicle engine, and complementary clutch elements on the adjacent ends of the stub shafts and the aligned cylinder drive shafts, said clutch elements being disengageable to permit elevation of the supplemental frame and cylinder.

9. A transit concrete mixer as in claim 6, the drive means comprising a shaft mounted on the supplemental frame at each side of the mixing cylinder, rollers on said shafts and tracks on the cylinder engaged thereby, 35 stub shafts supported from the truck chassis forward of the supplemental frame and each aligned with its respective shaft on the supplemental frame when the latter is in its normal running position, driving means connecting said stub shafts with the vehicle engine, complementary clutch elements on the adjacent ends of the stub shafts and the aligned cylinder drive shafts, said clutch elements being disengageable to permit elevation of the supplemental frame and cylinder, and a retaining frame supported on 40 said supplemental frame and encircling the upper portion of said mixing cylinder.

10. A transit concrete mixer as in claim 6, the drive means comprising a shaft mounted on the supplemental frame at each side of the mixing cylinder, rollers on said 55 shafts and tracks on the cylinder engaged thereby, stub shafts supported from the truck chassis forward of the supplemental frame and each aligned with its respective shaft on the supplemental frame when the latter is in its normal running position, driving means connecting said stub shafts with the vehicle engine, and complementary clutch elements on the adjacent ends of the stub shafts and the aligned cylinder drive 60 shafts, said clutch elements being disengage-

able to permit elevation of the supplemental frame and cylinder, and clutch control means located adjacent the driver's seat for operation while in transit.

11. A transit concrete mixer comprising 70 an auto truck, a supplemental frame supported on the truck chassis and movable relative thereto into dumping position, a rotative mixing cylinder, means for supporting said cylinder from the supplemental 75 frame, drive means operatively connecting said cylinder with the truck engine, means for elevating said supplemental frame and cylinder into dumping position, and a water tank carried upon said truck and communicating with the interior of said mixing cylinder.

12. A transit concrete mixer comprising an auto truck, a supplemental frame supported on the truck chassis and movable 85 relative thereto into dumping position, a rotative mixing cylinder, means for supporting said cylinder from the supplemental frame, drive means operatively connecting said cylinder with the truck engine and including complementary clutch elements supported respectively from the truck chassis and from the supplemental frame, means for elevating said supplemental frame and cylinder into dumping position, said clutch elements being disengageable to permit such elevation, a water tank carried upon said truck and communicating with the interior of said mixing cylinder, and clutch control means located adjacent the driver's seat for convenient operation while in transit.

13. A transit concrete mixer comprising an auto truck, a supplemental frame pivoted upon the rear end of the truck frame, a 105 hoist for lifting said frame into dumping position, a rotative cylinder having a discharge opening at its rear end, and cradled on said supplemental frame, means for driving said cylinder from the truck's engine, 110 a water tank separate from said cylinder, a water pipe from said tank communicating with the interior of said cylinder through its front end, and a valve in said water pipe located adjacent the driver's 115 seat.

14. A transit concrete mixer comprising an auto truck, including the several wheels, the power plant, and driver's seat, a rotative mixing shell mounted on said truck, 120 drive means operatively connecting said shell with the truck's power plant, a water tank carried by said truck, and communicating with the interior of said cylinder, and means located adjacent the driver's seat for admitting water from said tank to the interior of said shell.

15. A transit concrete mixer comprising an auto truck, including a chassis, drive and steering wheels therefor, the power 125

- plant, and the driver's seat, a rotative mixer shell mounted on said truck, drive means including complementary clutch elements, operatively connecting said shell with the truck's power plant, a water tank carried by said truck and a conduit connecting said water tank with the interior of said shell, said conduit including a portion disposed adjacent the driver's seat, a control valve in said portion and operable from the driver's seat, and means for controlling said clutch elements in the shell drive means from the driver's seat.
16. A transit concrete mixer comprising an auto truck, including a chassis, drive and steering wheels therefor, the power plant, and the driver's seat, a mixer element mounted on said truck, drive means, including a clutch, operatively connecting said mixer element with the truck's power plant, and means located adjacent the driver's seat for controlling said clutch, whereby operation of the mixer element may be controlled while in transit.
17. A transit concrete mixer comprising an auto truck, a cylindrical shell mounted
- thereon to rotate upon a horizontal axis, and having an opening in a cylindrical wall for charging said shell, means for driving said shell from the truck's power plant, said shell having a discharge opening at an end, and removable means, securable to and rotatable with the shell, for closing said charging opening and said discharge opening.
18. In a transit concrete mixer, comprising an automobile vehicle, a supplemental frame carried by the vehicle frame and adapted for elevation thereabove; a mixing element carried by the supplemental frame, drive means operatively connecting said mixing element with the vehicle drive mechanism whereby rotation can be imparted to the mixing element, said drive means including clutch elements disconnectable to permit the elevation of the supplemental frame above the vehicle frame with the supplemental frame inclined toward the rear of the automobile vehicle.

Signed at Seattle, King County, Washington, this 15th day of October, 1925.

HUGH PARK PARIS.
